UNITED STATES PATENT OFFICE.

EDGAR W. GOUGH, OF GREAT BARRINGTON, MASSACHUSETTS.

REGULATOR FOR ELECTRIC CIRCUITS.

No. 835,416.

Specification of Letters Patent.

Patented Nov. 6, 1906.

Application filed July 6, 1905. Serial No. 268,345.

To all whom it may concern:

Be it known that I, EDGAR W. GOUGH, a citizen of the United States, residing at Great Barrington, Berkshire county, State of Massachusetts, have invented certain new and useful Improvements in Regulators for Electric Circuits, of which the following is a full, clear, and exact description.

My invention relates to regulators for electric circuits for maintaining a constant condition on an electric circuit, and has for its object to provide a means whereby the current flowing from or the voltage impressed upon an electric circuit by a storage battery or other source of electricity having a series of generating elements can be maintained constant by cutting in or out one or more of the generating elements. It has for its object not only to produce this result, but to insure an automatic action by a device having certainty of action and in which the moving element shall travel between fixed positions, so as not to stop at a point where it will short-circuit any generating element.

The following is a description of an embodiment of my invention wherein it is used to maintain the potential constant, reference being had to the accompanying drawings, in which—

Figure 1 shows a plan view of the necessary elements of the apparatus. Fig. 2 shows a side elevation of the same on an enlarged scale. Fig. 3 shows a detail. Fig. 4 shows a diagrammatic view of the same in connection with proper relay mechanism.

Referring to the drawings, 1, 2, 3, 4, 5, 6, and 7 are contacts which are adapted to be connected to part of the generating elements of a source of electricity—such, for instance, as consecutive cells of a storage battery B, supplying the translating devices A, Fig. 4. These elements are at one end of the series of generating elements, the other end being connected to a main M'.

8 is a movable contact-piece adapted to connect one of the terminals 1 to 7 with the common terminal member 9, which is connected to the other main M'. The contact member 8 is carried by an arm 10, pivoted at 11, and having an extension 12 provided with a slot in which a pin 13 works. This pin is carried by a rod 14, upon whose ends are solenoid-cores 15 16, which are adapted to be drawn into the solenoids 17 and 18, respectively. The rod 14 is provided with a piston 19, which works loosely within a dash-pot 20,

filled with suitable liquid, so as to prevent too violent movement of the rod 14 when one or the other of the solenoids 17 and 18 is energized.

The arm 10 carries a solenoid 21, whose core 22 is electrically connected with one terminal of its winding. The other terminal of the solenoid 21 is connected to the arm 10, bearing on the member 9. The lower end of this core 22 enters one of a series of holes 23 in an insulating-strip 23^a, carried in the contact member 9, and makes electrical contact with one of a series of terminals 24, situated in proximity to each of said holes 23 and electrically connected together. The core 22 also carries the contact 25, insulated therefrom, which when the core is raised is adapted to make engagement with the terminal 26, which consists of a curved strip of copper, so that when the core 22 is raised contact is made, whatever may be the position of the arm 10.

As shown in Fig. 2, the contacts 24 are insulated from the base 9. The terminals 24 are electrically connected by a conductor 27 with the terminals 28 28'. The terminal 26 is electrically connected to the terminal 9. The contact 25 is connected to the windings of the pulling-solenoids 17 and 18, the other terminals of which solenoids are respectively connected to terminals 29 and 30, supported by the base 9 and insulated therefrom. In proximity to the terminals 29 and 30 are two relay-solenoids 31 and 32 whose L-shaped cores 33 and 34 when lifted are adapted to engage with said terminals 29 and 30, respectively, being separated from them when depressed by the insulation 29', on which they rest. These cores 33 34 are electrically connected together and also to a main M' of the circuit by the conductor 34^a. One terminal of the solenoid 31 is connected to a contact 35, and one terminal of the solenoid 32 is connected to a contact 36. The other terminals of the solenoids 31 32, as well as one terminal of the solenoid 21, are connected to the arm 10, which bears upon the member 9, which member 9 is electrically connected by the conductor 38 with the main M'. The solenoids 31 and 32 are, therefore, relays through which the main relay controls the circuit through the solenoids 17 18. The cores 22, 33, and 34 are insulated from the arm 10 by insulating-bushings 37.

The contacts 28 28' and 35 and 36 are adapted to be engaged by a movable member

40, preferably a polarized armature, pivotally mounted at 41 on the relay. This movable member is electrically connected by a conductor 42 to the main M' . The arrangement is such that when the movable member 40 is moved to the right contact is made simultaneously with both the terminals 28' and 36, and when moved to the left simultaneous contact is made with both the terminals 28 and 35. The element member 40 is normally in a central position between the poles of an electromagnet 43, which electromagnet has its coil 44 connected across the mains $M' M^2$. The movable member is kept in a central position against the attraction of the electromagnet 43 when normally energized by a spring 45 in conjunction with a counterweight 46, which permits of adjustment.

Referring further to the arrangement shown in Fig. 4, it will be seen that when the magnetism of the magnet 43 increases above the normal, such as would be the case when the voltage was too high, the lower end of the armature 40 would be attracted to the right, so that the terminals 28' and 36 would be electrically connected with the main M' . The connection of the terminal 28' with the main M' would result in a current flowing from main M' through conductor 42, armature 40, contact 28', terminal 24, core 22, solenoid-winding 21, brush 8, base 9, conductor 38 to the main M^2 . This would raise the core 22 so as to cause an electric contact to be made between terminals 25 and 26, thus connecting one terminal of each of the solenoids 17 and 18 with the main M^2 . When the core 22 is raised to the full limit, the engagement with contact 24 is broken. The engagement with terminal 26 is made before contact with 24 is broken. The core 22 is in the meantime withdrawn from the hole 23 in the base 9 and the insulation 23^a upon a movement of the arm 10 prevents its again falling until the next hole is reached, and thus maintains the engagement between contacts 25 26. When the next hole 23 is reached, the core 22 will fall if the armature 40 is not in engagement with either contact 28 28', since the solenoid 21 will be deenergized. A movement of the arm 10 is brought about through the action of one of the solenoids 31 32, the proper one being selected by the engagement of the terminals 35 or 36. The terminal 36 is engaged by the movable member 40 when it moves to the right and is thus put into connection with the main M' , a circuit being thus completed through the solenoid 32. As the core 34 of this solenoid is raised it makes electrical contact with the terminal 30. Since the cores 33 34 are always electrically connected with the main M' by the conductor 34^a, this engagement of the core 34 with the terminal 30 completes an electric connection from the main M' through

the core 34, terminal 30, winding of solenoid 18, terminals 25 and 26, brush 8, base 9, conductor 38 to the main M^2 , thus energizing the solenoid 18. This would move the arm 10 so as to cut out one or more of the generating elements. The arm would continue to move until the normal potential was reached.

In case the potential across the mains falls so that the spring 45 overcomes the attractive force of the electromagnet 43 and the polarized armature 40 moves to the left, so as to make engagement with the terminals 28 and 35, putting them into electrical connection with the main M' , the solenoid 21 would be energized as before. In this case, however, the solenoid 31, being controlled by the terminal 35, would be energized. This would result in causing the core 33 of that solenoid to make contact with the terminal 29, thus completing an electric circuit from the main M' through the solenoid 17 to the main M^2 . It will thus be seen that if the potential rises unduly the magnet 43 will be so energized as to attract the armature 40 to the right against the action of the spring 45, which would release the switch-arm 10 and energize the solenoid 18, with the result that one or more of the generating elements would be cut out until the normal potential was reached, while if the potential falls the armature 40 moves to the left and the solenoid 17 is energized so that the elements are cut in.

If after the switch-arm 10 is moved one step the armature 40 still remains in contact with one of the terminals 28 35 or 28' and 36, the same operation is immediately repeated. If, on the other hand, it is away from these contacts, the arm 10 remains in its fixed position, as above described.

The reason for inserting the two small solenoids 31 and 32 in the circuit instead of connecting the solenoids 17 and 18 directly across the contacts 35 and 36 is that it is necessary that after the arm 10 has once started it shall continue in its motion until it reaches the next intended point. In other words, it must never be left stranded between any two points, which would occur if the solenoids 17 and 18 were connected directly across the contacts 35 and 36 and if the armature 40 ceased to make contact at 35 or 36 after the arm had started on its travel but before it reached the next locking position. This is rendered impossible by means of the small solenoids 31 and 32, and the fact that after electric contact is once established through the movement of either core that core is carried by the moving arm so as to be moved past one of the projections 29² and 30², so as to be mechanically prevented from falling in case the engagement with the terminals 28 and 35 or 28' and 36 is broken. In this way the electric contact between the solenoid-cores 33 and 34 and the terminals 29 and 30 when once established electromagnetically

is maintained mechanically until the switch-arm has been moved a full step of its throw or until the next locking position is reached. When this movement is completed, the solenoid 33 or 34 is mechanically released so that the circuit through the solenoid 17 or 18 is broken until re-established by a suitable movement of the polarized armature 40.

It is of course understood that in moving from any contact 1 to 7 to another the switch-arm must overlap two contacts, the same as in any ordinary rheostat, in order to avoid interrupting the circuit entirely. Since in overlapping two contacts, however, the cell contained between those contacts is short-circuited, a large rush of current is apt to result unless some special form of contact is provided. I therefore provide a supplemental contact 50, connected through the high resistance 51 to the contact member 8, but otherwise separated from the contact 8 by insulation 52. In this construction as the member 8 leaves the contact the member 50 is still in connection with it and the short circuit which would result takes place over and through the resistance 51, which is made sufficient to prevent a short circuit at the low potential of one cell, but whose resistance is low enough to make no perceptible difference in the electromotive force of the circuit during the instant the change is being made from one position to another.

From the foregoing it will be seen that in my apparatus the elements are automatically cut in and out, as required, so as to maintain the potential constant, and means are provided for insuring that an element shall be completely cut in or cut out, or, in other words, means are provided whereby the switch-arm is always moved a complete step.

My invention permits of various modifications and applications, such as will be evident to those skilled in the art.

What I claim is—

1. In a regulator for electric circuits, the combination of a series of contacts, a switch-arm adapted to make engagement therewith, two power-solenoids adapted to be separately energized, two cores therefor connected together and to said switch-arm, a relay for closing the circuit through said solenoids one at a time, means for maintaining the circuit through either of said solenoids closed until a full step of said arm has been completed whenever such circuit has been closed and the switch-arm has moved a part of a step, said means being independent of circuit conditions.

2. In a regulator for electric circuits, the combination of a series of contacts, a switch-arm adapted to make engagement therewith, two power-solenoids adapted to be separately energized, two cores for said solenoids connected together and to said switch-arm, a relay for closing the circuits through said

solenoids, one at a time, means for locking said switch-arm at the end of each step and a solenoid for releasing said locking means whenever the circuit through one of said power-solenoids is closed.

3. In a regulator for electric circuits, the combination of a series of contacts, a switch-arm adapted to make engagement therewith, two power-solenoids adapted to be separately energized, two cores for said solenoids connected together and to said switch-arm, a relay for closing the circuits through said solenoids, one at a time, means for locking said switch-arm at the end of each step, a solenoid for releasing said locking means whenever the circuit through one of said power-solenoids is closed, separable contacts controlling both of the circuits of said power-solenoids, and a support for causing said locking means when withdrawn to maintain the circuit of the energized power-solenoid closed at said contacts, until a full step of said arm is completed.

4. In a regulator for electric circuits, the combination of a series of contacts, a switch-arm adapted to make engagement therewith, two power-solenoids adapted to be separately energized, two cores for said solenoids connected together and to said switch-arm, a main relay, auxiliary relays controlled thereby for closing the circuits through said power-solenoids, one at a time, contacts in the circuits through said power-solenoids closed by said auxiliary relays when energized, mechanical stops for maintaining said contacts in engagement during a full step of said switch-arm when the circuit through one of said power-solenoids has been completed and said switch-arm has made a partial movement.

5. In a regulator for electric circuits, the combination of a series of contacts, a switch-arm adapted to make engagement therewith, two power-solenoids adapted to be separately energized, two cores for said solenoids connected together and to said switch-arm, a main relay, auxiliary relays controlled thereby for closing the circuits through said power-solenoids, one at a time, separable contacts in the circuits of said power-solenoids adapted to be brought into engagement when said auxiliary relays are energized, means for maintaining said contacts in engagement during a full step of said switch-arm when the switch-arm has been partially moved, said means being independent of circuit conditions.

6. In a regulator for electric circuits, the combination of a series of contacts, a switch-arm adapted to make engagement therewith, two power-solenoids adapted to be separately energized, two cores for said solenoids connected together and to said switch-arm, a main relay, auxiliary relays controlled thereby for closing the circuits

through said power-solenoids, one at a time, separable contacts in the circuits of said power-solenoids adapted to be brought into engagement when said auxiliary relays are energized, means for maintaining said stops in engagement during a full step of said switch-arm when the switch-arm has been partially moved, means for locking said switch-arm at the end of said step, and a solenoid for releasing said locking means whenever one of said power-solenoids is energized.

7. In a regulator for electric circuits, the combination of a series of contacts, a switch-arm adapted to make engagement therewith, two power-solenoids adapted to be separately energized, two cores for said solenoids connected together and to said switch-arm, a main relay, auxiliary relays controlled thereby for closing the circuits through said power-solenoids, one at a time, separable contacts in the circuits of said power-solenoids adapted to be brought into engagement when said auxiliary relays are energized, means for maintaining said contacts in engagement during a full step of said switch-arm when the switch-arm has been partially moved, means for locking said switch-arm at the end of said step, a solenoid for releasing said locking means whenever one of said power-solenoids is energized, additional separable contacts in the circuits of said power-solenoids and stops for causing said locking means when withdrawn to maintain the circuit of the energized power-solenoid closed at said additional contacts, until a full step of said switch-arm is completed.

8. In a regulator for electric circuits the combination of a series of contacts, a switch-arm adapted to engage therewith, electromagnetic means for actuating said arm, an electromagnetic device carried by said arm and a locking member actuated by said elec-

tromagnetic device, said locking member controlling the circuit through said electromagnetic actuating means.

9. In a regulator for electric circuits the combination of a series of contacts, a switch-arm adapted to engage therewith, electromagnetic means for actuating said arm, an electromagnetic device carried by said arm, a locking member actuated by said electromagnetic device, and separable contacts in the circuit of said electromagnetic means controlled by said locking member.

10. In a regulator for electric circuits, the combination of a series of contacts, a switch-arm adapted to engage therewith, electromagnetic means for actuating said arm, an electromagnetic device carried by said arm, a locking member actuated by said electromagnetic device, separable contacts in the circuit of said electromagnetic means controlled by said locking member, and means for maintaining engagement between said contacts during a full step of said arm when said contacts have been brought into engagement and the movement of said arm has begun.

11. In a regulator for electric circuits, the combination of a series of contacts, a switch-arm adapted to engage therewith, electromagnetic means for actuating said arm, a circuit for said electromagnetic means, contacts for making and breaking said circuit, an electromagnetic device for causing said contacts to engage, said electromagnetic device being carried by said arm, and means for holding said contacts in engagement when they have once been brought into engagement and the movement of the arm has begun.
